UNITED STATES PATENT OFFICE.

HENRY A. RENKEN, OF NEW YORK, N. Y., ASSIGNOR TO F. WESEL MANUFACTURING COMPANY, OF BROOKLYN, NEW YORK, A CORPORATION OF NEW YORK.

ROUTING-MACHINE AND THE LIKE.

No. 852,577.

Specification of Letters Patent.

Patented May 7, 1907.

Application filed June 30, 1906. Serial No. 324,182.

To all whom it may concern:

Be it known that I, HENRY A. RENKEN, a citizen of the United States, residing in the borough of Brooklyn of the city of New York, in the State of New York, have invented certain new and useful Improvements in Routing-Machines and the Like, of which the following is a specification, reference being had to the accompanying drawings, forming a part hereof.

The object of this invention is to provide an attachment for routing machines and the like whereby such machines may be readily adapted to cut, rule or perform some other operation along a straight edge or in a straight line.

The invention is designed principally for use in connection with machines having an elbow lever for carrying a cutter or other working tool, such a machine, for instance, being shown and described in Letters Patent of the United States No. 622,832 dated April 11, 1899, and granted to Ferdinand Wesel; and in the present case the invention is illustrated as embodied in the machine shown and described in said Letters Patent.

In the drawings Figure 1 is a plan view of the machine with the attachment in place thereon. Fig. 2 is a view in side elevation.

Fig. 3 is a detail elevation showing the shaft of a swiveling bracket for guiding one arm of the elbow lever, and some of the means for moving said shaft; part of the figure being broken away and shown partly in section to illustrate the construction more clearly.

Fig. 4 is a similar view of the same parts looking in a direction at right angles to the plane of Fig. 3. Figs. 5 and 6 are sectional views looking down upon the planes indicated by the lines 5—5 and 6—6 respectively in Fig. 3. Fig. 7 is a detail plan and Fig. 8 is a detail elevation, of a roller guide for the end of one arm of the elbow lever.

For the purpose of the present description, it will be unnecessary to describe or even refer to all of the parts of a machine in connection with which the present invention may be employed.

As stated above, the present invention is illustrated as applied to the routing machine shown and described in Letters Patent of the United States No. 622,832 and in order to understand the application of the invention

it will suffice to refer briefly to this machine. Using the same reference characters, in referring to this machine, as were used in said Letters Patent, it will be seen from Figs. 1 and 2 of the drawings that a table B is supported upon a pillar or standard A which in turn rests upon a base A'. Above the table an elbow lever is provided for carrying the working tool which, in the case of Letters Patent No. 622,832, is represented by the cutter h⁶ (not shown in the present drawings). This elbow lever has a disk-shaped base d which turns freely on a disk-shaped flange d' mounted upon the table and said lever consists of a lever arm D and a second lever arm F pivotally secured thereto. Suitable driving connections for the working tool are illustrated and described in said Letters Patent but need not be referred to herein. As will be obvious, the working tool which is mounted upon the lever arm F, as illustrated in said Letters Patent, may be moved into any position above the table by moving the front or handle end F² of the lever arm F which in the present case is shown broken off and which rests upon a guide rail G at the front of the table. It will be clear that in order to move the working tool or cutter along a straight edge or in other words to move the arm F of the elbow lever or that portion of the arm F which carries the working tool or cutter in a straight line, will require the provision of some means for guiding the same. Such means, it is the object of the present invention to provide and they will now be described.

In the first place, in order that that portion of the arm F which carries the working tool or cutter may move in a straight line, it must be capable, as will be obvious, of a certain degree of movement of translation with respect to the pivotal point of the arm F upon the arm D. For this purpose the arm F is jointed and the two members thereof f⁵ and f⁶ are pivoted to each other at f⁷. Moreover, one of the members as f⁶ is provided with an arc-shaped slot f⁸ in which a thumb screw f⁹ having a flange f¹⁰ and threaded upon the member f⁵ is adapted to work, the said thumb screw and slot being provided for the purpose of rigidly connecting the two members of the arm F when it is desired to use the elbow lever in the ordinary manner and for

permitting the free movement of the member f^5 when it is desired to move that member along a straight line.

The means for guiding the member f^5 in a straight line comprises a swiveling bracket U at one end and some such a device as a roller V at the other end. The swiveling bracket is provided with a projection u which serves as a guiding piece and co-operates with a long guideway or slot f^{11} formed in the underside of the member f^5 to guide the rear end of the member f^5 . This bracket arm u may be mounted upon a suitable stationary base u' which is provided with suitable means such as a lug or detent u^2 adapted to engage in a corresponding recess in the bracket arm to hold the latter firmly in operative position. The bracket arm is moved into and out of operative position by handle W preferably near the front of the machine which is operatively connected with means for rotating the bracket and for raising and lowering the same upon the lug or detent u^2 . The means for rotating the bracket preferably comprise a rack w meshing with a pinion u^3 keyed to a shaft u^4 which is rigidly secured to the bracket arm and which is journaled in a bracket u^5 secured to the pillar A. This bracket may be formed with a long guideway for the rack w and also with a second long guideway for the reception of a corresponding flange w' upon a sliding wedge w^2 which serves at the proper time to draw the bracket arm U downwardly so that its recess fits upon the detent u^2 against the action of a spring u^6 coiled around the shaft u^4 between the bracket u^5 and a collar u^7 fast upon said shaft. Co-operating with the sliding wedge w^2 is a collar w^3 fitted loosely upon the lower end of the shaft and held thereon by nuts w^4 . The sliding wedge w^2 preferably has two arms or members which embrace the shaft u^4 and the collar w^3 is provided with a projection w^5 which fits between these two arms or members and is thus held from any rotation relative to the sliding wedge. The upper surface of said collar where it co-operates with each arm of the sliding wedge is inclined as indicated at w^6 in such a way as to co-operate with the sliding wedge to draw the shaft u^4 downwardly against the action of the spring u^6 , as will be obvious from Figs. 3 and 4. The handle W is secured to one arm of a bell crank lever w^7 which has pivoted thereto links w^8 and w^9 connected respectively to the rack w and the sliding wedge w^2 .

The roller V which, as before stated, serves to guide the forward end of the member f^5 may be journaled in a carrier v which is pivoted at v' to a bracket v² suitably secured to the guide rail G. Thus the roller may be swung into and out of operative position, it being held in operative position by some such means as a pin and slot connection, illustrated particularly in Fig. 7. The pin is

preferably provided with a spring v^3 contained in a suitable housing and acting upon the forward end of the pin which is enlarged for this purpose.

When the attachment is not in use, the roller v is allowed to drop into the position shown in dotted lines in Fig. 2 and the bracket arm U is swung out to the position indicated in dotted lines in Fig. 1. When it is desired to use the attachment, the arm F is swung toward the right in Fig. 1 and the handle W is depressed thus swinging the bracket arm U into position. It will be understood that when the bracket arm U is swung into position, the shaft u^4 will be raised enough by the spring u^6 to permit the bracket arm to swing around above the plane of the detent u^2 , and that the rack and sliding wedge are so related to each other that as soon as the bracket U has been swung into operative position, the wedge will act upon the collar w^3 and will depress the shaft u^4 thus bringing the bracket arm down so that the detent u^2 will engage the recess therein. When the bracket arm has been swung into operative position, the roller V is raised and fastened by means of the pin and slot connection above described in the position indicated in full lines in Figs. 2, 7 and 8. Then the lever F is brought into the position indicated in Fig. 1 with its end F² resting upon the roller V, and the screw f^9 is unfastened so as to free the member f^5 from the member f^6 . The device then is in readiness for cutting a straight edge or otherwise operating along a straight line. When it is desired to disconnect the attachment from the elbow lever and to use the machine in the ordinary manner, the lever is brought again into the position shown in Fig. 1, the handle W is raised thus swinging back the swiveling bracket U and the roller V is unfastened and swung down into the position shown in dotted lines in Fig. 2.

It will be understood that various changes may be made in the embodiment of the invention shown and described herein and that it is not limited therefore to the construction shown nor to the use in connection with which it has been particularly described.

I claim as my invention:

1. In a routing or like machine, an elbow lever one arm of which is jointed, and means to guide one member of said arm.
2. In a routing or like machine, an elbow lever one arm of which is jointed, and a movable bracket to guide one member of said arm.
3. In a routing or like machine, an elbow lever one arm of which is jointed, a swiveling bracket arm, and a roller to guide one member of said arm in a straight line.
4. In a routing or like machine, an elbow lever one arm of which is jointed and one member of which arm has a long guide-way

formed upon its under side, a swiveling bracket arm having a guide piece to co-operate with said guide-way, means to move said bracket arm into and out of operative position, and means to co-operate with the guide piece to guide said member in a straight line.

5. In a routing or like machine, an elbow lever one arm of which is jointed, means to secure the two members of said arm together, and means to guide one member of said arm in a straight line.

6. In a routing or like machine, an elbow lever one arm of which is jointed, a screw threaded on one of the members of said arm, 15 the other member of said arm having an arc-shaped slot in which the screw works, and means to guide one of said members in a straight line.

7. In a routing or like machine, an elbow lever one arm of which is jointed and one member of which arm has a long guide-way formed upon its under side, a screw threaded in one of the members of said arm, the other member of said arm having an arc-shaped 25 slot in which the screw works, a swiveling bracket arm having a guide piece to co-operate with the guide-way, means to move the bracket arm into and out of operative position and means co-operating with the guide- 30 piece to guide one of the members in a straight line.

8. In a routing or like machine, the combination of a lever, a swiveling bracket to guide the lever, a detent to hold the bracket 35 in position, and means to turn the bracket in position, and means to raise and lower the same upon the detent.

9. In a routing or like machine, the combination of a lever, a swiveling bracket to 40 guide the lever, a detent to hold the bracket

in position, means to turn the bracket and to raise and lower the same upon the detent, and a second lever to operate said means.

10. In a routing or like machine, the combination of a lever, a swiveling bracket to 45 guide the lever, a shaft for the bracket, a rack and pinion to turn the shaft, a sliding wedge, means upon the shaft to co-operate with the wedge, and a handle operatively connected with the rack and wedge. 50

11. In a routing or like machine, an elbow lever one arm of which is jointed and one member of which arm has a long guide-way formed upon its under side, a swiveling bracket arm having a guide piece to co-operate with the guide-way, a shaft for the bracket arm, a rack and pinion to turn the shaft, a sliding wedge, means upon the shaft to co-operate with the wedge, a handle operatively connected with the rack and wedge, 55 and a roller to co-operate with the guide piece to guide said member in a straight line.

12. In a routing or like machine, an elbow lever one arm of which is jointed, and means to guide said arm in a straight line. 60

13. In a routing or like machine, an elbow lever one arm of which is jointed, and a movable bracket to guide one member of said arm.

14. In a routing or like machine, an elbow 70 lever one arm of which is jointed, a swiveling bracket arm, and a roller to guide one end of said arm in a straight line.

This specification signed and witnessed this 19th day of June A. D. 1906.
